 Pa., a corporation of Pennsylvania

Application June 6, 1947, Serial No. 753,095

8 Claims. (Cl. 48—180)

1

The general object of the present invention is to provide improved gas mixing apparatus. More specifically, the object of the invention is to provide a simple and relatively inexpensive, but efficient gas mixing machine for use in supplying at widely varying rates a combustible mixture of air and gas under a pressure appreciably above atmospheric pressure. The invention was devised and is adapted for use in mixing machine units of relatively small capacity suitable for domestic use, and particularly for use in supplying a combustible mixture to the burners of kitchen gas ranges and water heaters, as well as for many industrial uses in which the heat requirement of the gas burner apparatus is relatively small.

It has long been generally recognized that in the operation of industrial gas burning apparatus having relatively large heat requirements, substantial technical and economic advantages are obtainable by premixing the gas to be burned with combustion air to form a combustible mixture containing predetermined proportions of gas and air, and supplying the mixture to the gas burning apparatus under a pressure considerably above the pressure of the atmosphere. So-called gas mixing machines for forming such combustible mixtures and supplying them under pressure to furnaces and other gas burning apparatus having relatively large heat requirements, are now in extensive and successful use. In general, the same kind of advantages are obtainable when a preformed combustible mixture of air and gas is supplied under pressure to gas burning apparatus having a relatively small heat requirement as when the mixture is supplied to apparatus having a relatively large heat requirement. Heretofore, however, no air and gas mixing machine for supplying a combustible mixture under pressure and having a relatively small output capacity, has been produced so far as I am aware.

A further specific object of the invention is to provide a mixing unit of relatively small capacity with improved simple, inexpensive and practically effective means for varying the air-gas ratio of the mixture. The capacity for such ratio adjustment is necessary to adapt the mixing unit for use with fuel-gases of different compositions and B. t. u. values. Moreover, in domestic use as in industrial use, a mixture having the air-gas ratio required for complete combustion will be desirable in some cases, while in other cases mixtures containing more or less air than is required for complete combustion, are desirable.

The various features of novelty which characterize my invention are pointed out with par-

2

ticularity in the claims annexed to and forming a part of this specification. For a better understanding of the invention, however, its advantages, and specific objects attained with its use, reference should be had to the accompanying drawing and descriptive matter in which I have illustrated and described preferred embodiments of the invention.

Of the drawings:

Figure 1 is a plan view of a mixing unit;
 Figure 2 is a view partly in section showing the internal arrangement of the mixing unit.

Figure 3 is a section on the line 3—3 of Fig. 2;
 Figure 4 is a section on the line 4—4 of Fig. 2;
 and

Figures 5 and 6 are sections taken similarly to Figure 4 and each illustrating a different modification of the ratio controlling apparatus shown in Figure 4.

The desirable embodiment of the present invention illustrated in Figures 1 to 4 comprises a centrifugal fan or blower housing structure A formed with an impeller chamber B. An impeller C mounted in the chamber B comprises a disc-like body with impeller vanes or ribs C' at the side of the impeller facing a central inlet opening D in the front wall b of the chamber B. At its periphery the fan housing structure is formed with a circular collecting channel E open at its inner edge to the impeller chamber B and having a tangentially extending outlet E'. The latter is shown as having a threaded end e for connection to piping for conveying the mixture to the gas burner or burners in which the mixture is to be burned. As shown, the impeller C is carried by the shaft F' of a driving motor F having its frame rigidly attached to the housing structure A, and having a base portion F² through which the mixing unit may be mounted on a suitable support. As shown, a bearing G for the shaft F' is interposed between the impeller C and the motor F.

In the particular form shown, air and gas pass into the impeller chamber B through the inlet opening D from a chamber H. The latter, as shown, is in the form of a box having its back wall formed by the impeller chamber wall b and having side walls H' connected to and extending away from said bottom wall, and having a removable front wall I, detachably secured to the side walls H' as by screws i. The side walls H' may be cast integrally with the adjacent side wall b, or may be welded to the latter, or the box H and impeller housing may be made of a suitable plastic material, as conditions make desirable. As shown, air and gas pass separately

into the chamber H through passages *ia* and *ig* through the front wall. As shown, said passages are the bores of tubular bosses IA and IG. Each of said bosses comprises an inner end portion at the inner side, and an outer end portion at the outer side of the plate-like front wall I. For the major portion of its length, each of the passages or bores *ia* and *ig* is of uniform cross-section, but as shown, the outer end portion of each passage is enlarged and internally threaded to form a threaded pipe receiving socket. As shown, an air supply pipe J has a threaded end portion in the socket formed in the outer end of the boss IA, and a gas supply pipe K is threaded into the socket in the outer end portion of the boss IG.

As shown, the pipe J receives air from the outlet of an air filter M which has its inlet M' open to the atmosphere, and the pipe K receives gas from the outlet of a gas governor N, which receives gas under a pressure above the pressure of the atmosphere through a pipe N' from a gas holder or other unillustrated source of fuel gas. The gas governor N comprises a pressure responsive means including a pressure chamber connected to the pipe J by the conduit N', and a valve automatically adjusted by the pressure responsive means as required to maintain a pressure in the pipe K equal to the pressure in the pipe J. The gas governor N may be of well known type, such, for example, as that shown in the Hess patent, No. 2,243,704 of May 27, 1941, and includes nothing claimed as novel herein, and hence does not need to be illustrated or further described herein.

In the desirable form of the invention illustrated in the drawings, the flow of gas into the chamber H from the pipe K, is variably throttled by a tapered valve or obturator OG. The valve OG may be, and as shown is, a cone approximately coaxial with the passage *ig* in all operative positions of the valve. In all throttling positions of the valve OG its apex is within the passage *ig* and a variable throttling action is obtained by adjusting the valve in the general direction of its axis.

In the no flow, or full throttling position of the valve OG, the latter extends so far into the passage *ig* that the inner end of said passage is closed by the engagement of the inner end of the wall surrounding said passage with the portion of the conical valve having the same diameter as the passage *ig*. The valve OG is mounted on the lower end of a valve supporting member P which also supports a tapered valve OA variably throttling the air passage *ia*. Since the mixture formed ordinarily contains substantially more air than gas, the diameter of the passage *ia* is usually considerably greater than the diameter of the passage *ig*. The valve members OA and OG extend into the passages *ia* and *ig*, respectively, for the same distances in all adjustments.

The purpose of the valves OG and OA is to proportionally increase and decrease the cross-sectional area of the annular space between the inner wall of each of the passages and the peripheral edge of the section through the corresponding valve on the plane of the inner edge of the bosses IA and IG, in all adjustments of the valves. To this end, the valve OA is in the form of a cone having a conical angle suitably different from that of the valve OG, so that the cross-sectional areas of the said annular spaces may remain in constant proportion to one another as the member P moves the valves from their wide open position in which the valves are wholly outside of passages *ia* and *ig*, and their fully closed positions

in which the inner end of each passage is filled by a base portion of the corresponding valve.

As shown, the valve supporting member P is in the form of a vertically disposed skeletonized, or grid-like link having lower end portions P' to which the valves OA and OG are connected and having spaced apart upper end portions P² pivoted on aligned horizontal pivot pins I² mounted in brackets I' carried by the removable front wall 10 of the chamber H. In the closed positions of the valves, the center of gravity of the link P and the valves supported by it, is to the right of the vertical plane including the axes of the pivots I² as seen in Figure 2. In consequence, the valves are at all times subjected to a gravitational bias force tending to hold the valves in their closed positions. When the fan is drawing air and gas out of the chamber H through the port D, the fluid streams flowing into the chamber H through the 15 passages *ia* and *ig*, subject the valve members to a differential pressure action which diminishes as the lengths of the valve portions in the passages are diminished. With any given rate of flow through the chamber H, the valves come to rest 20 in the position in which the pressure differential action on the valves due to the streams of air and gas entering the chamber H, equals the gravitational bias force tending to move the valves in their closed positions.

30 When the valve members OA and OG are in their fully closed positions, they are coaxial with the passages *ia* and *ig*, respectively, entered by the valves. As the supporting member P turns counter-clockwise as seen in Figure 2 to give an 35 opening movement to the valves, the axes of the valves are similarly turned out of alignment with the axes of the passages *ia* and *ig*, but with the parts proportioned generally as shown, the divergence between the axis of each valve and the axis 40 of the corresponding passage is slight, and of no practical consequence, particularly as said divergence diminishes as the throttling effect of the valve is increased.

As shown in Figure 2, the valve member OA is 45 provided with a stem extending through the corresponding link portion P' and anchored in place by a nut O² on a threaded end portion of the stem. The valve OG may be similarly connected to the link P. When it becomes necessary to 50 change the ratio of gas to air in the mixture produced as in adapting the mixture for use with different fuel gases having different combustion air requirements, as to town gas and natural gas, for example, the relative flow capacities of the 55 passages *ia* and *ig* must be varied. Such variation can be effected in various ways. For example, as illustrated in Figure 5, the passage *ia* may then have its effective internal diameter reduced by a tubular liner Q externally threaded for screw 60 thread engagement with an internally threaded portion of the passage *ia*. When the diameter of the air passage is thus reduced, the valve OA shown in Figure 2 is replaced by a valve OA' having a corresponding smaller conical angle to maintain the same air to gas ratio with the valves OG and OA' in their different throttling positions.

The air to gas ratio maintained with apparatus of the general character shown in Figure 4, may be reduced without the use of the liner Q shown in Figure 5, by substituting a valve OA'' of the character shown in Figure 6 for the valve OA shown in Figure 4. The valve OA'' comprises a tapered portion of the same effective or stream varying length as the valves OG, OA and OA', and an axial cylindrical extension OA³ at the 70 75

smaller end of the tapered portion of the valve OA''. Different reductions in the air to gas ratio may be secured by the interchangeable use of valves having cylindrical portions OA³ with different diameters. To secure the same reduction in the air to gas ratio which is obtainable by the conjoint use of the valve OA' and liner Q of Figure 5, the cross-sectional area of the cylindrical extension OA³ of the valve OA'' should be equal to the cross-sectional area of the liner Q. As will be understood, for each different air to gas ratio obtained by the interchangeable use of valves OA'' of the general form shown in Figure 6, the effective stream varying, tapered portion of each valve OA'', must increase in cross-sectional area as the distance from the adjacent end of the cylindrical portion OA³ of the valve, increases in the same proportion as the cross-sectional area of the valve OG increases as the distance from the apex end of that valve increases. This means that the tapered portion of the valve OA³ is not a cone but is a conoidal body, the surface elements of which are inclined to the axis of said body at an angle which increases slightly as the distance from the junction of the tapered and cylindrical portions of the valve increases.

My improved gas mixing machine is obviously characterized by its structural and operational simplicity and reliability, and is further characterized by the fact that it may be embodied in sturdy, compact units of relatively low capacities which can be manufactured at a relatively low cost. Such units may well have mixture output capacities varying from about one hundred cubic feet per hour to one thousand cubic feet per hour. Units having such capacities are economically efficient for uses in which the amount of mixture used is too small to justify the use of the larger and more costly gas mixing machines, which heretofore have been the only equally efficient devices available for supplying combustible mixtures under pressure and with an air-gas ratio remaining constant with wide variations in mixture output. The invention may also be used in units having capacities substantially greater than one thousand cubic feet per hour, as well as in units having mixture capacities of less than one hundred cubic feet per hour.

The varying inclination of the axes of the valves OA, OA' and OA'' and OG, to the axes of the flow passages *ia* and *ig* with which the valves are associated, results in slight changes in the form of the annular proportioning orifice portions of the flow paths through the passages *ia* and *ig*. The orifice portion of each flow path is the portion having the smallest cross section i. e., the inner end portion of the flow path through the corresponding passage *ia* or *ig*. Such changes in the orifice shape are without practical importance, however, because the changes in shape of the two orifices are small and similar, and also because of the fact in normal operation the mixture demand is usually approximately constant most of the time, so that the obturator valves are held in nearly constant positions most of the time.

While in accordance with the provisions of the statutes, I have illustrated and described the best forms of embodiment of my invention now known to me, it will be apparent to those skilled in that art that changes may be made in the forms of the apparatus disclosed without departing from the spirit of my invention as set forth in the appended claims, and that in some

cases certain features of my invention may be used to advantage without a corresponding use of other features.

Having now described my invention, what I claim as new and desire to secure by Letters Patent, is:

1. Air and gas mixing apparatus comprising a centrifugal fan housing structure formed with a pair of chambers including an impeller chamber and an inlet chamber and a partition wall between said chambers and formed with an inlet port opening into said impeller chamber from said inlet chamber and with an inlet chamber wall having separate side by side air and gas inlet passages extending through it, a rotary impeller in said impeller chamber, a valve structure for similarly throttling gas and air streams passing into said inlet chamber through said passages comprising a separate throttling valve for each passage and a common supporting member for the valves, means to mount said valve structure for free swinging movement around a pivot, the pivot for said valve structure being to one side of the center of gravity thereof so that it is biased for movement of the valves in a direction which is opposite to the direction of flow of said streams through said passages to increase the throttling effect of the valves on said streams whereby said valves are maintained in positions displaced from the inlet passages by amounts increasing with the quantity rate of fluid flow through said passages.
2. Apparatus as specified in claim 1, in which said valves are in form of tapered obturators having their apex ends normally received in said passages.

3. Apparatus as specified in claim 1, in which said valves are in form of tapered obturators having their apex ends normally received in said openings and having their cross-sectional areas varying along their lengths so as to maintain a constant proportion between the minimum cross-sectional area of the flow paths in the two passages.

4. Apparatus as specified in claim 1, including an electric motor having a rotor connected to and rotating said impeller and a motor frame mechanically connected to said fan housing structure.

5. Apparatus as specified in claim 1, including an electric motor having a rotor connected to and rotating said impeller and a motor frame mechanically connected to said fan housing structure and supporting the latter.

6. In an air and gas mixing apparatus, a housing having a mixing chamber provided with a wall, said wall being provided with side by side ports for air and gas, a throttling valve for each of said ports, a supporting means for said valves, means to mount said supporting means on said wall for pivotal movement whereby said valves may be moved into and out of said ports, said supporting means being shaped so that the center of gravity thereof is to one side of the mounting means so that it has a bias in a direction to close said valves, and means to withdraw air and gas from said chamber to thereby cause said supporting means to move against its bias to let air and gas flow into said chamber past said valves.

7. Air and gas mixing apparatus comprising structure forming a chamber having a pair of walls, an inlet opening for air and an inlet opening for gas located side by side in one of said walls, a frame, a valve for each of said openings attached to said frame, means to mount said frame

for free swinging movement on said structure in said chamber so that said valves may be moved into and out of restricting position with respect to said openings, said frame being shaped so that the center of gravity thereof is to one side of the mounting means so that it has a bias to move said valves in a direction to close said openings, a port in the other of said walls, and means mounted on said structure to withdraw gas and air from said chamber through said port to thereby produce a pressure drop across said valves whereby said frame and valves will be moved against their bias to permit gas and air to flow into said chamber through their respective gas and air inlet openings.

8. Air and gas mixing apparatus comprising a centrifugal fan housing structure formed with an impeller chamber and with an inlet chamber and a partition wall between said chambers and formed with an inlet port opening into said impeller chamber from said inlet chamber and with an inlet chamber wall having separate side-by-side air and gas inlet passages extending through it, a rotary impeller in said impeller chamber, a valve structure for similarly throttling gas and air streams passing into said inlet chamber through said passages comprising a separate throttling valve for each passage, a common supporting member for the valves, means to mount said valve structure for free swinging movement, said valve structure being biased for movement of the valves in a direction which is opposite to the direction of the flow of said streams through said passages and which increases the throttling

effect of said valves on said streams whereby said valves are maintained in positions displaced from the first-mentioned positions by amounts increasing with the quantity rate of fluid flow through said passages, said passages being substantially horizontal, said throttling valves being tapered bodies each having its small end within the corresponding opening and said supporting member being suspended in said inlet chamber from an upper portion of said housing structure to turn about a horizontal axis above said passages and horizontally displaced from the center of gravity of said valve structure to subject said valve structure to a gravitational bias tending to move said bodies far enough into said passages substantially to prevent flow therethrough.
